HEAT TREATING FURNACE

Henry A. Drefein, Chicago, Ill.

Application November 28, 1930
Serial No. 498,669

9 Claims. (Cl. 263—8)

This invention relates to heat treating furnaces and has for an object to provide a furnace in which heat treating of metal, such as metal sheets, may be conducted as, for example, to effect normalizing thereof with subsequent rapid cooling in a reducing or non-oxidizing atmosphere.

Another object is to provide a furnace for heat treating metal sheets or the like, as, for example, to a temperature which will effect normalizing, and thereafter quickly and satisfactorily cooling the same in a minimum of time in a reducing or non-oxidizing atmosphere.

Another object consists in the provision of a furnace with improved combustion and heat supplying means; in the provision of such a furnace in which the flow of the heating gases is toward the charging end of the furnace; the provision of such a furnace with a cooling chamber extension in which cooled products of combustion are utilized to accelerate the cooling of the metal sheets, or the like; the provision of such a furnace in which the cooling gases are utilized to baffle or obstruct the flow of hot gases from the heating chamber into the cooling chamber; and the provision of means to contribute to the cooling of the metal sheets in the cooling chamber and simultaneously to preheat the air utilized for combustion of the fuel in the heating furnace.

Other objects reside in the details of the structure hereinafter described in the following specification and illustrated in the accompanying drawings, in which

35 Figs. 1a, 1b and 1c are a horizontal section of the entire furnace structure;
Figs. 2a and 2b are a vertical section of said furnace, an intermediate portion thereof being omitted for convenience;

40 Fig. 3 is a vertical section along the line 3—3 of Fig. 1b;

Fig. 4 is a similar section along the line 4—4 of Figs. 1a and 2a;

45 Fig. 5 is a vertical section along the line 5—5 of Fig. 1c;

Fig. 6 is a similar section along the line 6—6 of Fig. 1c.

Like numerals refer to like elements throughout the drawings.

50 In Figs. 1a and 1b are illustrated in horizontal section the major portion of the heating chamber of the furnace structure generally indicated by numeral 10, the same extending to the restricting baffle 11 (see Figs. 1c and 2b), at which point begins the cooling chamber, generally designated by numeral 12. The walls and floor of the heating and cooling chambers are formed of suitable refractory, there being slots 14 in the floor of the chambers to permit the passage of 55 conveyer members for the continuous convey-

ance of metal sheets, or the like, through the furnace structure. At the entrance or charging end of the heating chamber is provided a vertically adjustable door 16 (see Fig. 2a), and similarly there is provided an adjustable door 17 at 65 the discharge end of the furnace (see Fig. 2b).

I have found it expedient and desirable to use for heat generation and supply the invention disclosed in my Patent No. 1,779,964 issued October 28, 1930, although I do not wish to be restricted to the specific combustion units except as limited to details thereof by the claims. At one side of the heating chamber adjacent the charging end thereof the wall is offset at 18 to accommodate a burner 19 into and through 70 which I introduce at substantial velocity an admixture of fuel and air, such as producer gas and air. Opposed to the burner 19 and spaced therefrom is a restricted chamber 20, formed by the wall 21, there being a gap 22 between one 75 end of said wall and the offset furnace wall 18. At the top of the wall 21 are ports or passages 23 (see Fig. 2a) formed by the partitions 23a extending upward from the top of the wall 21. These partitions 23a are inclined in such wise as 80 to direct the gases flowing out of the chamber 20 into the heating chamber proper partially toward the entrance end of the heating furnace. The restricted chamber 20 is terminated at the end opposed to the burner 19 by the wall 25, at 85 the opposite side of which is another restricted chamber 27 formed by a partition wall 28 having partitions 28a extending upward from the wall 28. These partitions are substantially at right 90 angles to the major axis of the furnace structure. In alignment with the restricted chamber 27 is the burner 30 similar to burner 19, there also being a similar gap 31 between the burner and the wall 28.

These combustion units function similarly. 100 Burning fuel mixture is introduced, as stated, at substantial velocity through or from the burner 19 whence it flows toward and into the restricted chamber 20, for example, past the gap 22, radiant heat being transmitted there across 105 but without substantial contact of the burning gases with the product passing through the furnace. A pressure is set up in the restricted chamber 20 and the products of combustion flow therefrom through the ports 23 adjacent the 110 roof of the furnace structure, transversely of the same, over, around and in contact with the metal sheets, for example. The flow of gases into the restricted chamber 20 is such as to set up an inductive action whereby a portion of 115 the products of combustion is induced into recirculation with the gases flowing into the restricted chamber. Due to the inclination of the partitions 23a, the flow of gases from the restricted chamber 20 is such as to enhance or aid 120

the general flow of gases in the furnace toward the charging end thereof. As stated, a similar action obtains in the opposed adjacent burner unit except that the gases flow from the restricted chamber 27 at right angles to the general flow of the gases through the heating chamber.

At the opposite side of the furnace is provided a similar pair of burner units generally indicated by numerals 33 and 34, being staggered with respect to the first described units. The function and operation is identical with those previously described. The side walls of the furnace are offset or inset to accommodate the burners affording easy access to the air supply ducts 35 and gas supply ducts 36 for adjustment or regulation.

The supply of fuel and air is preferably such that pressure is set up in the heating chamber in excess of atmospheric to prevent infiltration of air. The arrangement of the ports from the respective restricted chambers is such as to assist or enhance the general flow of gases toward and out the charging end of the heating chamber. With the burner units of the character described and arranged as described, products of combustion will be successively picked up and recirculated in part as they pass each heating unit, so that some of the gases are repeatedly reheated and recirculated in their travel through the heating chamber, which contributes markedly to the efficiency of operation. Also with the heat supply means described, relatively few burners are required, which makes for flexible and positive control and operation.

Also since the sheets or other product being heated, are received at the charging end at a relatively low temperature, they are met by the outflowing gases and encounter an increasing temperature as they flow toward the discharge end of the furnace since, as their temperature increases, they exercise a lesser cooling action upon the products of combustion. Another advantage resides in the fact that the gases during combustion thereof need not be contacted with the product, but only products of combustion which eliminates the hazardous stratification of air and fuel which might cause oxidization of the sheets. It also reduces the deposit of soot, tarry substances or the like upon the sheets.

Forming a continuation with the heating chamber is the cooling chamber 12, there being a restricting transverse wall or baffle 11, previously described, with an opening 11a therethrough to permit the passage of the sheets and the conveying means. Leading from the heating chamber, preferably at the charging end thereof, is the outlet 40 communicating with the extended exterior duct 41 having the initial portion 41a thereof insulated in the embodiment illustrated.

This duct 41 is located above the furnace structure and leads to an exhauster or fan 43, shown as driven by an electric motor 44 through the medium of a belt 45. From the fan 43 leads the elbow or delivery pipe 47 through the top of the cooling chamber 12. Extending upwardly from the roof of the cooling chamber adjacent its juncture with the heating chamber is a plurality of vent pipes or stacks 49, each of which is provided with an adjustable damper 50.

Extending transversely through the cooling

chamber intermediate its extremities is a plurality of air pipes 52, terminating at each end in a manifold or header 53-54, these headers being located on the outside of the cooling chamber for convenience. Communicating with the header 53 is the duct 55 also in communication with a motor driven fan 56, which supplies atmospheric air to the header 53, pipes 52 and header 54. From the last, leads a duct 57 and a branch duct 58, the former communicating with the adjacent burner to supply air thereto, and the latter to the opposed burner as illustrated in Fig. 1b. Similarly a branch 59 is provided to supply air to the burners on the opposite side of the heating chamber. Pipes 52 are located above the plane of travel of the sheets in the cooling chamber and in the embodiment shown begin a substantial distance from the restricting wall 11.

A motor 60, speed reducing mechanism 61 and chain 62 together with suitable sprockets furnish driving power for the shaft 63, which carries sprockets 64 for actuation of the conveyer mechanism which may be of any suitable construction.

In the operation of the apparatus described above, metal sheets, for example, are continuously fed into the heating chamber through the charging end thereof where they encounter the outflowing heated gases. They are subjected to an increasing temperature as they travel toward the discharge end of the heating chamber until the desired maximum is reached, as for example, from 1750° F. to 1950° for normalizing. The heated gases of combustion, as stated above, flow rearwardly from the discharge end of the heating chamber toward the charging end thereof, a portion of said gases being picked up in their flow past each of the restricted chambers and induced into recirculation with the incoming burning or burned gases for subsequent delivery into the heating chamber proper. From the heating chamber the sheets travel into and through the cooling chamber 12, arriving therein at a maximum temperature. During this travel through the cooling chamber they are submitted to the cooling action of the products of combustion which have been extracted from the heating chamber by the exhauster 43 through duct 41. These cooling gases are delivered downwardly and upon and around these sheets as they are about to pass out of the cooling chamber, so that the flow of cooling gases is toward the heating chamber. During this flow of the cooling gases they encounter sheets which are of increasing temperature so that the cooling gases are raised in temperature to a maximum where they encounter the sheets at their maximum temperature when they are passed from the heating chamber into the cooling chamber. This insures against subjecting the sheets to a marked drop in temperature as they pass from one chamber to the other, while at the same time their temperature is rapidly but more or less uniformly reduced to the desired point when they leave the cooling chamber.

The heated cooling gases, as they approach the barrier 11, in part at least, will then flow upwardly and back along the roof of the cooling chamber, and in part those beneath the sheets will be forced rearwardly along the floor of the cooling chamber for outward flow through the discharge opening of the furnace. The spacing of the orifices 48' permits this discharge of the upper rearwardly flowing hot gases.

The pipes 52 conveying air at atmospheric temperature serve materially to cool or contribute to the maintenance of the cooling gases in relatively cooled condition in their flow in the 5 cooling chamber, thus contributing to the rapid cooling of the sheets. At the same time the heat which is extracted from the cooling gases by the air in the pipes 52 serves to preheat such air prior to its delivery to the burners, which 10 also adds to the efficiency of operation as will be readily recognized by those skilled in the art. The long travel through the duct 41 permits the substantial radiation of heat from the extracted gases and products of combustion, so that they 15 are very substantially reduced in temperature before they are discharged into the cooling chamber. The operation of the exhauster 43 may be controlled to set up any desirable pressure in the cooling chamber, so that the pressure 20 of the gases in the heating chamber may be balanced or, if desired, overbalanced by the pressure of the cooling gases, so that the latter serve to baffle or obstruct the flow of heating gases and prevent their substantial entry into the cooling 25 chamber. A damper 41b is provided in duct 41 on suction side of exhauster 43 for control of gas flow through duct 41 and consequent cooling effect. In this wise cooling gases are or may be utilized to initiate and contribute to the rearward flow of the heating gases toward the charging 30 end of the furnace as described above.

An increase in the quantity of the product being handled by the furnace may require an increase in the cooling action in the cooling chamber, 35 in which event an increased delivery of cooling gases may be required. In such event, in addition to use of the damper 41b, the dampers 50 in the vent pipes or stacks 49 may be adjusted to permit the necessary discharge of cooling 40 gases into the atmosphere, thereby permitting an increased delivery of such cooling gases without increasing the amount thereof which are recirculated in the cooling chamber.

By the construction and process described 45 above, I am enabled to use a relatively very short length of cooling chamber with respect to the associated heating chamber. In fact, in a furnace of approximately overall length of one hundred feet I have been able to devote seventy 50 feet thereof to the heating chamber and thirty feet thereof to the cooling chamber while obtaining temperatures of 1750° F. to 1950° F. in the heating chamber with a reduction of the temperature of the sheets in the cooling chamber before discharge thereof to from 800° F. to 55 1200° F., i. e. to a dull red heat or therebelow.

With this furnace it is possible therefore to anneal or normalize materials by first raising them to a suitable high temperature and then rapidly but uniformly cooling them to any desired low temperature, such as a dull red heat for example, before they leave the furnace, and at the same time maintain in both the heating and cooling chambers of the furnace a non-oxidizing atmosphere.

The advantage of being able to devote as much as possible of the length of a furnace of this character to the annealing normalizing or other heating operation will be readily appreciated by those skilled in the art, particularly as the cost of such structures is more or less proportional to the length thereof. Therefore, the less such structures are utilized for cooling the greater capacity and efficiency which will be obtained.

It will be obvious that my structure and ap-

paratus are susceptible of modification and I do not wish to be restricted to the forms illustrated and described, except as I may be so restricted by the appended claims properly interpreted with respect to the prior art.

80

What I claim is:

1. A furnace of the class described comprising a heating chamber and a cooling chamber in alignment therewith, means to supply heating gases to said heating chamber, and means to deliver cooled products of combustion into said cooling chamber toward said heating chamber, said last named means being constructed and arranged to direct said cooled products of combustion toward said heating chamber.

85

2. A furnace of the class described comprising a heating chamber, means to supply heating gases thereto, said means including a burner and a restricted chamber and opposed thereto provided with ports communicating with said heating chamber, said ports being directed at an angle to assist flow of heating gases in said heating chamber toward the charging end thereof.

90

3. A furnace of the class described comprising a heating chamber and a cooling chamber, means to supply heating gases to said heating chamber, a duct leading from said heating chamber to said cooling chamber, an exhauster associated therewith to extract gases from said heating chamber and deliver them into said cooling chamber, gas delivery means in said cooling chamber, said duct being in communication therewith, said gas delivery means being constructed and arranged to direct said cooling gases from the discharge end of said cooling chamber toward the charging end thereof.

95

4. A furnace of the class described comprising a heating chamber and a cooling chamber, means to supply heating gases to said heating chamber, means to deliver gases of combustion from said heating chamber into said cooling chamber adjacent the discharge end thereof, and a vent pipe leading from said cooling chamber adjacent the entrance end thereof.

100

5. A furnace of the class described comprising a heating chamber having a charging end and a cooling chamber having a discharging end, means to supply heating gases to said heating chamber, a duct leading from said heating chamber adjacent the charging end thereof and leading to said cooling chamber adjacent the discharge end thereof, and means to effect flow of gases from said heating chamber through said duct.

105

6. A furnace of the class described comprising a heating chamber having a charging end and a cooling chamber having a discharging end, means to supply heating gases to said heating chamber, a duct leading from said heating chamber adjacent the charging end thereof and leading to said cooling chamber adjacent the discharge end thereof, said duct being located exteriorly of said furnace whereby said gases will be cooled in travel therethrough.

110

7. A furnace of the class described comprising a heating chamber having a charging end and a cooling chamber having a discharging end, means to supply heating gases to said heating chamber, a duct leading from said heating chamber adjacent the charging end thereof and leading to said cooling chamber adjacent the discharge end thereof, and means to effect flow of heating gases from said heating chamber through said duct, said duct being located ex-

- teriorly of said furnace, whereby said gases will be cooled in travel therethrough.
8. A furnace of the class described comprising a heating chamber and a pair of adjacent oppositely directed restricted chambers at one side thereof, a burner in alignment with each of said restricted chambers, said furnace being further provided with ports leading from said restricted chambers into said heating chamber, the ports from one of said restricted chambers being inclined at an angle less than a right angle
- with respect to the major axis of said heating chamber.
9. A furnace of the class described comprising a cooling chamber having a discharge end, means to deliver cooled non-oxidizing gases thereinto, said means including spaced orifices constructed and arranged at said discharge end to deliver gases away from said discharge end upon sheets passing therethrough.
